UNITED STATES PATENT OFFICE.

LEWIS H. FALLEY, OF KANSAS CITY, MISSOURI.

ORE CLASSIFYING AND SEPARATING APPARATUS.

1,307,626.

Specification of Letters Patent. Patented June 24, 1919.

Application filed July 2, 1918. Serial No. 243,055.

To all whom it may concern:

Be it known that I, LEWIS H. FALLEY, a citizen of the United States, residing at Kansas City, in the county of Jackson, State 5 of Missouri, have invented certain new and useful Improvements in Ore Classifying and Separating Apparatus, of which the following is a full specification.

The present invention relates to apparatus 10 for use in mining operations for the classification and separation of various ores from chats or tailings.

One of the objects in view is to devise an improved apparatus utilizing a water flow 15 charged with the ore particles and so controlled as to deposit the particles of ore according to their proper classification at intervals during the course of the flow through the apparatus.

20 To this end, the invention comprises an apparatus composed of one or more settling tanks through which the course of the ore-charged water is, by improved means, so controlled and directed, and the rate of flow 25 so regulated, that the ore particles are divided out and separated and discharged therefrom according to the classification desired. This improved means comprises a certain novel partition and baffle structure for 30 subdividing the tanks into compartments of proper proportions and acting to break up and direct the water flow in the required manner, together with auxiliary water supply means whereby the character of the 35 water flow and separating action may be further regulated.

It is also sought to devise a simple and economical construction of the character described, which may be cheaply manufactured and also installed and operated at a 40 minimum of expense.

With these general objects in view, as well as minor objects which will appear in the course of the detailed specification, the 45 invention will now be described with reference to the accompanying drawings illustrating one form of construction which has been devised for embodying the proposed improvements, after which the novel features therein will be set forth and defined in the appended claims.

In the drawings—

Figure 1 is a central longitudinal vertical section showing an apparatus constructed 55 in accordance with the present invention;

Fig. 2 is a plan view of the same;

Figs. 3 and 4 are broken vertical sectional views, on an enlarged scale, taken on the lines 3—3 and 4—4, respectively, of Fig. 1;

Fig. 5 is a transverse section taken on the 60 line 5—5 of Fig. 1, and also on an enlarged scale; and

Fig. 6 is a detail section taken on the line 6—6 of Fig. 5, and on a still larger scale.

Referring to the drawings in detail, the 65 apparatus is shown as comprising a plurality of settling tanks, 8, 10, 12, 14 and 16, gradually increasing in area of cross-section in the order given, these tanks being constructed of any suitable material, such 70 as cypress wood, and each being provided with a hopper bottom portion as shown in Fig. 1, and with a discharge pipe 18 for the outlet of the classified ore product.

The upper cylindrical portions of the 75 tanks 8, 10, 12, and 14 are divided, by means of vertical partition members 20, into downflow compartments 8', 10', etc., and upflow compartments 8'', 10'', etc., said downflow compartments being of larger cross-section 80 than the upflow compartments. The partitions 20 are preferably constructed of sheet metal, and of approximately V-shape, with their side edges mounted slidably in guides 22. Each partition is formed at its lower 85 end with a passage 24 allowing communication between the compartments of each tank, and the partitions of the tanks 8, 10 and 12 are further formed with one or more openings 26 above the opening 24 for providing 90 communication between said compartments at different elevations above said opening 24.

Associated with each opening 26 is a deflecting element 28 arranged to impart a direct upward flow to the water immediately 95 after entering the upflow compartment through said opening, said deflecting element being formed as a part of a baffle member 30 intersecting the lower margin of the opening 26 and extending transversely of 100 the tank and at a downward incline to approximately the middle thereof. The baffle members 30 are secured to their corresponding partitions 20 (as by soldering) and serve to support said partitions adjustably within 105 the tank, for which purpose the members 30 are carried by pins 32 adjustably mounted in a series of sockets 30 provided therefor in the side walls of the tanks (see Fig. 4). At each of the openings 26 is supported 110

the lower end of a baffle or deflecting member 36 which projects upward from the lower edge of the opening 26 and extends at an incline across the larger compartment to the opposite wall thereof. The lower end of each baffle or deflecting member 36 is supported on the adjacent deflecting member 30, and the upper end of each member 36 is adjustably supported on pins 32 for each of which also a plurality of sockets 34 are provided in the side walls of the tank. Each deflecting member 36 thus coöperates with one of the baffle members 30 to form a transverse partition across the larger compartment of the tank. The baffle or deflecting members 36 are of general V-shape in cross-section (see Fig. 4) gradually approaching a straight line at their lower ends, and the angle in each member 36 is formed with a plurality of openings 38 varying in diameter as clearly shown in Fig. 5. At the base of each partition 20 is provided a transverse partition 36', similar to the members 36, but extending entirely across the tank and beneath the partition 20, said partition 36' being supported at both its ends by means of the pins 32 adjustably mounted in sockets 34. Preferably said partition 36' is provided with only one of the openings 38, adjacent the opening 24, while the lower corners of said partition are cut away to provide the passages 40, as illustrated in Fig. 2, communicating with the lower or hopper portion of the tank.

35 An auxiliary water supply connection 42 is located in position to feed water into the compartment 8' of the tank 8, and a second water supply pipe 44 is located in position to feed an auxiliary supply of water, as needed, into the lower hopper portion of said tank, each of said supply connections being provided with a suitable regulating valve 46.

45 The sludge or ore-charged water is discharged into the compartment 8' from a chute or trough 48 or the like, and similar chutes or troughs 50 are arranged to carry the overflow from the compartment 8'' to the compartment 10' and from the compartment 10'' to the compartment 12'. The overflow is discharged from the compartments 12'' and 14'' simply by means of notch passages 52 cut in the dividing walls of the tanks.

55 The overflow from the tank 14 is merely compelled to follow a zigzag course up and down around a series of vertical partitions in the tank 16, the water passing through passages 53 under a pair of partitions 54, and over an intermediate partition 56, which latter is also provided with a bottom opening 58 (see Fig. 1) permitting some of the ore particles already deposited to reach the discharge outlet 18 from the tank 16. The final discharge of the waste and surplus

water takes place by way of a discharge trough 60 which delivers to the tailings pile or pond.

In the operation of the apparatus, the ore-carrying water is received into the larger compartment 8' of the tank 8, and the flow follows a zigzag path downward through said compartment, being deflected back and forth by the described baffle structure; at the same time the various sizes of openings 38 in the transverse partitions also act to break up and more or less vary the rate of flow at different points within the compartment, so that a certain mild degree of agitation of the ore charged water is maintained within the compartment 8' sufficient to keep the suspended ore particles constantly moving and thereby facilitating the separating out of the same at the proper intervals. At different elevations within the compartment 8' a part of the flow is bypassed through the openings 26 into the smaller compartment 8'', and the deflecting elements 28 insure that such flow is given an immediate upward movement on entering said compartment. Such bypassed portions of the water flow of course carry off the lighter particles of the ore in suspension, and the balance of the main current or flow is turned backward at the bottom of the tank and up through the passage 24 into said smaller compartment 8''. This upward flow of the main body of the current is so regulated that the heavier or coarser particles will settle back upon the partition 36' and through the same into the bottom of the tank 8, while most of the lighter particles will be carried upward through the smaller compartment 8'' and on into the remaining tanks for further classification. Additional water may be admitted through the connections 42 and 44 at the top and bottom of the tank, as required, for the further regulation of the water current and the separating action being effected thereby.

60 It is apparent that a quicker flow takes place in passing upward back of the partition 20 and no opportunity is afforded for any material deposits of the particles within the smaller compartment, but on passing into the tank 10, a further separating action is at once started and carried out in practically the same manner as in the tank 8; an additional factor, however, lies in the fact that the tank 10 is of greater cross-sectional area than the tank 8 so that the rate of water flow is correspondingly diminished, which check of the current in itself enhances the separating action of the tank 10. Otherwise the action of the tanks 10, 12 and 14, is in general but a prolonging of the same effect as is produced by the first tank 8. The function of the tank 16 will be readily understood, the separation taking place principally by ordinary precipitation

which is assisted by the slow upward flow in the second and fourth compartments of said tank, the final classification being thus effected and collected at the base of the middle compartment, whence it is withdrawn by way of the outlet 18, the waste being discharged from said tank over the trough 60.

It will thus be seen that a simple and efficient arrangement and construction of apparatus have been devised for carrying out the desired objects of the invention. A more perfect classification is obtained by the improved construction as well as a more constant feed to the collecting tables, it being seen that a more continuous separating action is effected by said improved construction by reason of the fact that a constant mild agitation is present throughout the downflow of the water and at the same time parts of the flow containing the lighter ore particles are being continually removed or bypassed away from the main flow without passing to the bottom of each tank and interfering with or lessening the effectiveness of the further separating action therein. An increase in effectiveness is also obtained by the provision of the auxiliary water supply connections whereby perfect control of the entire water flow is secured by increasing or diminishing the water supply at either the feed or discharge end of the tank, as required; obviously this auxiliary water supply may be applied to each tank of the apparatus under any conditions rendering the same advisable.

By adjusting the relative elevations of the partition structures, or the parts thereof, by means of the adjustment of the supporting pins 34, a still further regulation of the separating action may be obtained. It is also possible to regulate the upward flow through the smaller compartments by the mere insertion, if desired, of a piece or section of solid material (none being shown) whereby a reduction in the cross-section of such compartment is readily effected.

Thus by means of the improved construction a more perfect control and regulation of the classification, *i. e.*, an increased flexibility and range of classification, is made possible, and moreover, sub-classifications may be secured from each primary classification by simply feeding the same, by gravity, to an apparatus of smaller size.

It is further apparent that the improved apparatus requires no direct application of power for its operation, nor the use of any screens whatsoever, and also that a minimum supply of water from the mine pumps will be required.

A further feature of advantage lies in the fact that the construction is such as to make the interior of the tanks readily accessible for adjustment or removal or renewal of any of the parts therein.

While I have described and illustrated what is now deemed to represent the preferred form of embodiment of the improvements, I desire to expressly reserve the right to make such formal changes or modifications as may fairly fall within the scope of the appended claims.

Having described the invention, what I claim is:

1. An ore separating and classifying apparatus comprising a settling tank, and a partition dividing said tank into a downflow settling compartment and an upflow settling compartment having an outlet at its upper end, said partition having a plurality of openings at different elevations for providing communication between said compartments, and deflecting elements associated with said openings and having downwardly inclined portions extending into the downflow compartment and approximately vertical portions projecting upward in said upflow compartment in position to produce an immediate vertical flow of the material on entering the latter compartment. 90

2. An ore separating and classifying apparatus comprising a settling tank, a partition dividing said tank into a downflow settling compartment and an upflow settling compartment having an outlet at its upper end, said partition having a plurality of openings at different elevations for providing communication between said compartments, and deflecting elements supporting said partition within said tank, said elements being associated with said openings in position to produce an immediate vertical flow of the material on entering said upflow compartment. 100

3. An ore separating and classifying apparatus comprising a settling tank provided with means for maintaining a constant downflow of the ore-carrying material therethrough, and an inclined transverse partition within said tank, said partition being provided with a plurality of openings of different sizes producing unequal rates of flow through said partition. 110

4. An ore separating and classifying apparatus comprising a settling tank, a partition dividing said tank into a downflow compartment and an upflow compartment having an outlet at its upper end, said partition having a communicating passage at its lower end between said compartments and also an opening intermediate its ends providing communication between said compartments, and a perforated transverse partition in said downflow compartment extending on an incline downward to the lower margin of said opening. 120

5. An ore separating and classifying apparatus comprising a settling tank, a partition dividing said tank into a downflow settling compartment and an upflow settling 130

- compartment having an outlet at its upper end, said partition having a plurality of openings at different elevations for providing communication between said compartments, combined vertical and inclined deflecting elements supporting said partition within said tank, and adjustable supporting means in engagement with said deflecting elements.
6. An ore separating and classifying apparatus comprising a settling tank, a partition dividing said tank into a downflow compartment and an upflow compartment having an outlet at its upper end, said partition having a communicating passage at its lower end between said compartments and also an opening intermediate its ends providing communication between said compartments, a perforated transverse partition in said downflow compartment extending on an incline downward to the lower margin of

said opening, and means providing for vertical adjustment of said partitions within said tank.

7. An ore separating and classifying apparatus comprising a series of settling tanks, said tanks being of successively increasing cross-sectional area, each of said tanks being provided with a partition dividing the same into a downflow settling compartment and an upflow settling compartment communicating at their lower ends at some distance above the bottom of the tank, said upflow compartments being all of substantially the same cross-sectional area and each upflow compartment being provided with an overflow into the downflow compartment of the next succeeding tank of larger cross-sectional area.

In witness whereof I hereto affix my signature.

LEWIS H. FALLEY.
